[57] CLAIM

The ornamental design for a swing seat, substantially as shown and described.

DESCRIPTION

FIG. 1 is a top plan view of a swing seat embodying my new design;

FIG. 2 is a bottom plan view thereof;

FIG. 3 is a side elevational view thereof;

FIG. 4 is an enlarged end elevational view thereof; and FIG. 5 is an enlarged sectional view along line 5—5 of FIG. 1.

The side and end not shown are the same as the side and end shown.

FIG. 1

FIG. 2

FIG. 3

FIG. 4

FIG. 5
